CLAIM

The ornamental design of a condensate trap housing, as shown and described.

DESCRIPTION

FIG. 1 is a perspective of a housing of the present invention; FIG. 2 is another perspective thereof; FIG. 3 is a front elevation thereof; FIG. 4 is a right side elevation thereof; FIG. 5 is a top plan thereof; FIG. 6 is a left side elevation thereof; FIG. 7 is a rear elevation thereof; and, FIG. 8 is a bottom plan thereof.

The dash dot lines immediately adjacent to the claimed area represent the boundaries of the claimed design. The dashed lines in the figures illustrate the portions of the design that form no part of the claimed design. None of the broken lines form any part of the claimed design.
